BLANK HANDLING MACHINE

Nels A. Anderson, Stockton, Calif., assignor to
 Fibreboard Products Inc., San Francisco, Calif.,
 a corporation of Delaware

Application January 29, 1940, Serial No. 316,170

11 Claims. (Cl. 93—49)

My invention relates to a machine for folding a box blank and for securing portions of the folded blank together; and more particularly to a machine for folding a fiber shipping case and for stitching overlapping portions of the case in collapsed position.

It is among the objects of my invention to provide a machine for automatically handling box blanks to produce a superior product at less cost.

Still another object is to provide a machine for folding a blank accurately to produce a collapsed box which when set up has square corners and properly registered sealing flaps.

A further object is to provide a folding and conveying mechanism coacting with a stitching device to maintain the blank edges properly squared-up during the stitching operation.

Another important object of my invention includes the provision of a safety device for stopping a stitcher after a predetermined number of stitches have been made to prevent injury to the stitcher head in event a blank becomes jammed in the mechanism.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a plan view of a box blank upon which my machine operates; and

Figure 2 is a similar view of the blank folded and stapled in collapsed position.

Figure 3 is a side elevational view showing half of the machine; and

Figure 4 is a similar view showing the other half.

Figure 5 is a fragmentary sectional view of the stitcher mechanism looking in a direction from the opposite side of the machine shown in Figure 4, and illustrating my safety attachment for the stitcher.

Figure 6 is a fragmentary perspective view of the blank engaging shoe into which the blank slides after leaving the folding mechanism.

Figure 7 is a plan view of the intermediate portions of the machine, showing the folding devices.

Figure 8 is a transverse vertical sectional view taken in a plane indicated by line 8—8 of Figure 7, illustrating details of a folding arm; and

Figure 9 is a longitudinal vertical sectional view of the feeder mechanism.

Figures 10 to 16, inclusive, are sectional and plan views showing the blank and coacting elements at operative positions in the machine.

In the past it has been the practice to fold slotted and creased fiber box blanks, such as shipping case blanks, by hand, and feed them manually into a stitcher mechanism. Aside from the labor problem and slowness of production, one of the chief difficulties was to get a uniform, properly stitched product. If a folded blank is not stitched square with edges accurately aligned, the box when finally set up will not have square corners, or, if the untrue box is forced into square position a gap will occur between flaps which should otherwise abut. In order to overcome these problems I have developed a machine which automatically handles the blank material and insures the production of uniformly folded blanks, each of which is stitched square.

In terms of broad inclusion, my blank handling machine comprises means for feeding and conveying the blanks; means for folding the blanks while traveling through the machine; means for aligning and squaring-up the blanks during the folding and fastening operations; and means for fastening portions of a folded blank together. The latter means preferably comprises an ordinary stitcher for driving staples through lapping portions of the blank. A safety device is also preferably provided for the stitcher to prevent damage to the stapling head in event a blank becomes jammed in the stitcher.

In greater detail, and referring to Figures 1 and 2 of the drawings, my preferred machine is designed to fold and stitch a fiber blank such as used for shipping cases. For example Figure 1 shows a creased and slotted blank 2 having closure flaps 3 and a fastening tab 4. Such a blank is folded along the crease lines 6 to the collapsed position shown in Figure 2 with tab 4 underlapping the adjacent end wall, and the parts are secured together as by metallic staples 7. The user receives the cases in this collapsed condition. It is understood that this blank is shown merely for purposes of illustration, and that my machine may be employed for folding box blanks of other kinds and in conjunction with fastening means other than a stitcher, as will be apparent from the following description of the machine.

Feeding and conveying mechanism

Referring particularly to Figures 3 and 9, the flat blanks are stacked in the machine in a hopper 8 mounted at one end of the main frame 9.

This hopper lies below the bed of the machine and has a head plate 11 against which the leading edges of the blanks abut, although accurate alignment of the blanks in the stack is not necessary. The blanks are stacked with flaps 3 leading and trailing, and with tab 4 at the back side of the machine, considering the side shown in Figure 3 to be the front.

Means are provided for lifting the top blank from the stack and for positioning its forward edge in the elevated plane of the machine bed. For this purpose a series of say four suction devices are arranged above the stack, each having a vacuum cup 12 mounted at the base of a hollow stem 13 slidable within a hollow supporting tube 14. Air is withdrawn from the cup through a flexible suction hose 16 attached to the top of tube 14. By this telescoping arrangement the vacuum cup may drop to the level defined by the upper blank of the stack, which level of course recedes with each blank removed. Up and down movement of stem 13 is controlled by a lever 17 fixed to a shaft 18 extending transversely of the frame, and carrying a pin 19 engaging slot 21 in a link 22 pivoted to the lower end of the stem. The lever thus elevates cup 12 to a predetermined level but allows the cup to drop varying distances.

After the cup has been elevated it is caused to swing forwardly about the axis of an overhead shaft 23 to which supporting tube 14 is fixed. Shafts 18 and 23 are turned by suitable crank linkages 24 and 25 actuated by cams 26 and 27 mounted on a cross shaft 28 journaled on the main frame. The latter shaft is driven by a chain 29 extending forwardly along the frame to a shaft 31, which in turn is driven by a chain 32 from a suitable motor 33.

Suction hoses 16 are connected to risers 34 from a manifold 36, and the latter is connected to a suitable vacuum pump 37 by a duct 38. A separate motor 39 drives the pump. Vacuum is impressed and released in the cups by a valve disc 41 covering an opening in the manifold; the valve being lifted by a lever 42 actuated by linkage 25 through a slotted link 43. When the valve is up and the manifold ported to the atmosphere there is no suction at the cups, as will be readily appreciated. The timing of course is such that valve 41 closes when the cups are lowered against a blank in the hopper.

These suction devices are preferably arranged to engage the four leading flaps of the blank, leaving a margin of flap material ahead of the vacuum cups for engagement by starter feed rolls 44 and 45 which function to advance the blank into the nip of main feed rolls 46 and 47. Lower starting roll 44 is positively driven through gears 48 from shaft 49, while upper roll 45 is freely journaled and is mounted for up and down movement on an arm 51. This arm is pivoted on a shaft 52 and is rocked by a linkage 53 actuated by a cam 54 on shaft 28. Timing of the arm movement is such that roll 45 is lowered to press the blank against roll 44 when the suction devices have deposited the leading edge of a blank between the rolls. Fixed bars 55 having upturned ends function to guide the blank between the rolls.

Opening of valve 41 is timed to release the vacuum at the cups just prior to engagement of roll 45 with the blank, whereupon the starter rolls advance the blank into the nip of main feed rolls 46 and 47 which are mounted on shafts 49 and 52 respectively. As soon as the blank is

caught between the latter rolls the upper starter roll 45 is lifted from the blank. There are a plurality of sets of these various feed rolls spaced across the machine, say two pairs of each, to provide positive feed for the blank. After the vacuum has been released at the cups, shaft 23 turns back to reposition tubes 14, and shaft 18 turns to lower the vacuum cups upon the stack. Valve 41 then closes to reestablish the vacuum at the cups.

Rolls 46 and 47 advance the blank upon a conveyor comprising a pair of chains 56 running on suitable sprockets on shafts 49 and 51. Lugs 57 spaced along the chains engage the trailing edge of a blank and advance it along the machine bed. The pusher lugs are accurately aligned in pairs on the chains to square the trailing edge of the blank with the center line of the machine. Since the rear conveyor sprockets are on shaft 51 the chains are driven by motor 33; and inasmuch as the forward sprockets are on shaft 49 the conveyor chains also function as a drive for the feed rolls, roll shafts 49 and 52 being preferably geared together.

Folding mechanism

As a blank advances along the bed it is supported adjacent the center by a T-bar 58 and adjacent the sides of the chains by angle bars 59. See Figures 7 and 10. The projecting end portions of the blank are supported by an angle bar 61 and a T-bar 62, the former having an upstanding flange against which the edge of the blank may bear. Angle bars 63, shown in Figures 7 and 11, are also provided above the blank to form straightedges about which the blank is folded on the crease lines 6. These latter bars are supported at their head ends only on a cross beam 64 so that the folded blank may slide off the tail ends of the straightedges.

Means are also provided on the bed to register creases 6 accurately with the straightedges. This is accomplished by a tapered strip 66 placed in the angle of bar 61 to shift the blank laterally into proper alignment. As the blank travels along the bed it is thus gradually eased over by the tapered strip until accurate registration obtains with the overhanging straightedges. See Figure 11.

Means are provided for folding the end portions of the blank over the intermediate portions thereof. This is done while the blank is in motion by pairs of pivoted folding arms 67 having elongated nose pieces 68 therebetween for engaging the blank alongside straightedges 63. These arms swing from retracted positions underlying the path of the blank to extended positions overlying the blank, thus folding the end portions of the blank over the straightedges. As shown in Figure 8, shaft 69 of an arm in each pair has a pinion 71 engaging a rack 72 which is reciprocated by a follower 73 riding on a cam 74 on a stub shaft 76. The latter is driven through gears 77 from a second stub shaft 78 carrying a sprocket 79 meshed with a conveyor chain. A spring 81 holds the follower against the cam. This driving of the folding mechanism from the conveyor chains simplifies the timing of these parts.

As the blank portions are folded the portion carrying tab 4 is moved down ahead of the other portion to obtain the underlying tab relationship. The blank portions are guided in this lapping order by bars 82 and 83 hung by heavy springs 84 from beam 64 to give a yieldable struc-

ture. See Figures 3 and 12. These bars slope downwardly and converge in the direction of blank movement to bring the folded portions of the blank together. After being folded by arms 67 the blank passes under fixed rods 85 which keep the turned-over portions from springing up. The folded blank is also confined laterally at this time by flanges 86.

In order to accommodate blanks of different size, the supporting angle bar 61 is mounted for transverse adjustment by screws 87; and the conveyor chains 56 and adjacent supporting bars 59 are mounted for like adjustment by screws 88. The folding arms, being mounted on the chain rider bars 89 as shown in Figure 8, are likewise adjusted by screws 88. Naturally the straight-edges must also be adjustable, and this is provided for by slidably mounting bars 63 on cross beam 64 as illustrated in Figure 3.

Stitcher mechanism

Means are provided for feeding and guiding the folded blank toward a stapling head 90 of the stitcher mechanism. As the leading edges of the folded blank leave the conveyor they are caught between pairs of feed rolls 91 and the blank is moved ahead faster than the conveyor speed to pull the blank away from the conveyor lugs so that the latter may rotate downwardly over the sprockets. As shown in Figure 4, the lower rolls are mounted on a shaft 92 drivably connected with shaft 31 by a chain 93; the upper rolls being mounted on a spring pressed shaft 94 geared to the lower roll shaft. Guide bars 82 and 83 underlying the folded portions of the blank terminate in an S-shaped channel 96 forming a pair of guideways through which the lapping edges of the blank slide. This channel is suitably fastened to the frame of the machine and thus provides support for the tail ends of the guide bars without interfering with the blank movement. See Figures 6 and 14. The upper and intermediate plates of the channel have upturned extensions 97 and 98 at the forward ends to insure engagement of the blank edges with the channel. The lower plate of the channel terminates in a rearwardly projecting extension 99 forming a clincher bar for the staples. This bar overlies an anvil 101 for support against the stapling blow.

Means are also provided for squaring the folded blank under the stapling head 90 to bring adjacent edges of the folded blank into registration and thereby square the folds along the crease lines. As the trailing edges of the blank leave rolls 91 these edges are engaged by a pair of pusher feet 102 each freely pivoted to a crank arm 103 oscillated by a cam 104 through a linkage 106; the cam shaft 107 being driven from shaft 31 by a chain 105. The lower ends of pusher elements 102 rest freely on the bed of the machine and ride over and drop behind a blank traveling under the pusher devices. Feet 102 then advance the folded blank against a trip 108 located in the path of the blank. Trip 108 is an element commonly associated with stitcher mechanisms and moves forwardly under the pressure of the advancing blank to start the stitcher, after which the trip is depressed to clear the blank.

Trip 108 and pusher feet 102 have normally upright opposing faces of sufficient height to engage both layers of the folded blank, and since trip 108 offers some resistance to movement the blank is subjected to a certain amount of edge-wise compression, sufficient to true up the edges

if they are not in absolute vertical alignment. As shown in Figure 15, pusher feet 102 are spaced to engage the trailing edge of each overlying blank portion, and trip 108 is centrally disposed to engage the leading edges of both overlying portions. Upon driving of the first staple, trip 108 is depressed by the stitcher mechanism to clear the leading edge of the blank.

Stapling head 90 and associated trip 108 may be of any suitable construction, and may comprise parts of the well-known "Latham" stitcher mechanism. Other parts of the Latham stitcher are also preferably employed, such as trigger 109, stitch spacing feed rolls 111 and discharge rolls 112. The stitcher parts are normally mounted on a sub-frame 113 which I preferably slidably mount on an extension 114 of my main frame, whereby the stapling head may be adjusted longitudinally of the main frame to determine the position of the first stitch relative to the blank. In accordance with the usual operation of a stitcher mechanism of this kind, the advancing blank first depresses trigger 109 which conditions the mechanism for operation, and then pushes trip 108 which engages a clutch to start operation of the stapling head. Other mechanism of the stitcher then comes into play to rock an arm 116 and lower the upper stitch spacing feed roll 111 against the folded blank. These rolls are driven intermittently to advance the blank between stitches. After the trailing edge of the blank rides off trigger 109 the stapling head stops and arm 116 is rocked to lower upper discharge roll 112 against the stitched blank to deliver it from the machine.

Safety mechanism

In using the Latham stitcher I have found that if a blank becomes jammed in the mechanism so as to hold trigger 109 down, the stapling head continues to drive staples in the same place and causes damage to the head. To avoid this I provide a safety device which stops the head after a predetermined number of staples have been driven. In order to orient this device with the stitcher mechanism, Figure 5 shows trigger 109, latch arm 117, stapling head shaft 118, cam 119 and control lever 121, all of which are standard parts of the Latham stitcher.

When trigger 109 is depressed by a blank it causes latch arm 117 to bear against the roller end of lever 121. Subsequent movement of trip 108 by the blank then starts the stapling head, one stitch being made for each revolution of its shaft 118. Upon rotation of shaft 118 the cam 119 depresses lever 121 and the notch of latch arm 117 engages over the lever roller to hold the lever down. Depression of lever 121 keeps the stapling head in operation and brings other mechanism into play to lower the stitch spacing roll 111 against the blank. When the trailing edge of the blank rides off trigger 109 the latter retracts latch arm 117 to release lever 121, which stops the stapling head and causes discharge roll 112 to be lowered against the blank.

My safety device comprises an arm 122 pivoted about a shaft 123 journaled in the sub-frame 113. At one end of shaft 123 is fixed a ratchet 124 engaged by a pawl 126 carried by arm 122. A cam plate 127 is removably secured to the ratchet and has a series of peripheral lobes 128 adapted to engage a catch 129 on latch arm 117 for releasing lever 121 when a lobe rides under the catch. A suitable brake 131 on the other end

of the shaft prevents the ratchet from overrunning.

By this arrangement arm 122 is oscillated by cam 119 and cam plate 121 is turned through an arc defined by one ratchet tooth for each revolution of shaft 118. Thus, the distance between lobes 128 limits the number of stitches that can be made before the stapling head is stopped, should a blank become stuck in the mechanism. With the twelve lobed cam shown in Figure 5 the stapling head will be stopped after five staples have been driven. By replacing cam plate 121 with one of the same diameter but having a different number of lobes, the stapling head may be stopped after a greater or less number of stitches, depending upon the spacing between the lobes.

While I have chosen to show a stitcher mechanism in conjunction with my blank feeding and folding mechanism it is understood other fastening means, such as a taping device, may be employed for securing the edges of the folded blank together.

The operation of my machine has been described largely in connection with a single blank, but it is understood that blanks follow each other in rapid succession through the machine. Conveyor chains 56 move continuously and lugs 57 are spaced therealong to engage the blanks as fast as they are deposited upon the conveyor by the feeding mechanism, the spacing of the lugs being such that they engage the trailing edge of a blank upon emergence from the nip of feed rolls 46 and 47. While a blank has an intermittent motion in the stitcher the series of stitches are made very rapidly in the "Latham" unit. Furthermore, the speeding up of the blank by rolls 91 prior to entering the stitcher allows for a certain amount of lost time in the stitching unit before the next set of conveyor lugs bring up another blank. The conveyor chains are thus enabled to move continuously.

I claim:

1. A machine for handling a blank, comprising means for folding the blank, elements between which the folded blank is compressed for registering adjacent edges of the blank, and means controlled by one of said elements for fastening portions of the folded blank together.

2. A machine for handling a blank, comprising means for folding the blank, means for stitching the folded blank, a trip engageable by the blank for actuating the stitching means, and means associated with said trip for squaring the fold prior to stitching.

3. A machine for handling a blank, comprising a conveyor chain for moving the blank, means adjacent the conveyor for folding the blank, and means actuated by a drive sprocket meshed with the conveyor chain for operating the folding means.

4. A machine for handling a blank, comprising means for moving the blank, means for folding portions of the blank into lapping relation, and an S-shaped element providing a guideway through which the lapping portions are slideable.

5. A machine for handling a blank having a crease, comprising means for moving the blank along a path, a straight edge, means for shifting the blank transversely of said path while the blank is in motion to register the crease with the straightedge, and means for folding the blank over said straightedge.

6. A machine for handling a blank having a crease, comprising means for moving the blank along a path, a fixed member having a surface angularly disposed to said path and engageable with an edge of the blank for shifting the blank transversely of said path while the blank is in motion to register the crease with the straightedge, and means for folding the blank over said straightedge.

7. A machine for handling a blank having portions adapted to be folded over the body of the blank with the ends of said portions overlapped, comprising means for moving the blank along a path, means for folding said portions, means for guiding said portions into predetermined lapping relation, means for applying pressure across opposite edges of the folded blank to square the folds, and means for fastening the lapping portions together.

8. A machine for handling a blank having portions adapted to be folded over the body of the blank with the ends of said portions overlapped, comprising means for moving the blank along a path, means for folding said portions, a pair of guide bars above said path for guiding said portions into predetermined lapping relation and spring means for resiliently suspending said bars.

9. A machine for handling a blank having portions adapted to be folded over the body of the blank with the ends of said portions overlapped, comprising means for moving the blank along a path, means for folding said portions, and a pair of angularly disposed guide bars arranged above the path and converging toward one end of the machine for guiding said portions into predetermined lapping relation.

10. A machine for handling a blank having portions adapted to be folded over the body of the blank with the ends of said portions overlapped, comprising means for moving the blank along a path, means for folding said portions, a pair of separate guide bars arranged above the path for guiding said portions into predetermined lapping relation, means for supporting the bars at one end, and a terminal element connected with the other ends of said bars and providing a guideway along which the lapping ends of said portions are slideable.

11. A machine for handling a blank, comprising means for moving the blank along a path, means adjacent the path for folding the blank, an element pivotally mounted above the path and arranged to be lifted by said blank and to ride over the blank and drop behind the trailing edges thereof, and means for moving the element forwardly against said edges to square the fold.

NELS A. ANDERSON.
